UNITED STATES PATENT OFFICE.

MAURICE MATHY, OF LIEGE, BELGIUM.

APPARATUS FOR COOLING MATERIALS.

1,385,636.

Specification of Letters Patent. Patented July 26, 1921.

Application filed July 17, 1919. Serial No. 311,606.

To all whom it may concern:

Be it known that I, MAURICE MATHY, manufacturer, a subject of the King of Belgium, and resident of Liege, in the Kingdom of Belgium, have invented certain new and useful Improvements in and Relating to Apparatus for Cooling Materials; and I do hereby declare the following to be a full, clear, and exact description of the invention, such as will enable others skilled in the art to which it appertains to make and use the same, reference being had to the accompanying drawings, and to letters or figures of reference marked therein, which 15 form a part of this specification.

This invention has for its object to provide an improved refrigerating apparatus comprising a cooling conveyer composed of an endless band for conveying the material 20 to be cooled through a closed box through which a current of cold air is arranged to flow. The improved apparatus is characterized by the feature that the current of cold air in its passage through the box, passes 25 first above the upper stretch of the endless band, to the end of the box, and then in its return journey passes through the lower part of the box.

According to the degree of cooling which 30 it is desired to produce, this return of the cold air can take place either through the space comprised between the two stretches of the endless band, or through the space situated under the lower stretch, or simultaneously through both these spaces.

The separation between these various spaces is effected by the endless band itself which rests with its edges upon horizontal surfaces carried by the sides of the box. 40 The passage from one space to the other at the end of the box is rendered possible by the provision of an enlargement of the box at that point.

The cold air enters the apparatus through 45 a hopper which distributes it over the entire width of the upper part of the box.

According to the present invention it is an advantage to use always the same air by causing it to travel in a closed circuit. This 50 circuit comprises a fan for driving the air into a refrigerator situated immediately in front of the inlet of the air in the cooling conveyer. On leaving the refrigerator the air passes through an air-drying device before reaching the suction orifice of the fan.

This arrangement has the advantage of constantly utilizing the same air which can therefore be kept as pure as possible, free from dust, microbes, etc. Moreover, the cold still contained in the air issuing from the 60 conveyer is not lost because the air is returned into the circuit.

The improved apparatus is adapted to treat materials to be cooled which are in the form of thin layers and especially chocolate.

The accompanying drawings illustrate by way of example a practical form of the invention.

Figure 1 is a longitudinal section of the 70 improved apparatus according to this invention on the line A B of Fig. 2.

Fig. 2 is a plan of the apparatus, after partial removal of the top of the box.

Fig. 3 is a partial section on the line C—D 75 of Fig. 2 drawn to a larger scale than Figs. 1 and 2.

Fig. 4 is a vertical cross section on the line E F of Fig. 2.

Figs. 5 and 6 are respectively a side elevation and a plan of the complete apparatus drawn to a reduced scale.

The improved apparatus comprises essentially a closed box 4 and a conveyer composed of an endless band 1 and two drums 35 2, 2'. The endless band passes around these drums and travels throughout the entire length of the box. These drums are situated outside the box and are driven by any suitable means.

The box is provided inside at a level with the lower surface of the upper stretch of the endless band and on its side walls with two U bars 14 fixed to longitudinals 10. The webs of these bars serve to support the 95 sides of the said stretch. Close to the point where the upper stretch passes out at 3 from the box, these bars are interrupted and the box is enlarged.

It is advisable to make a part of the sides 100 of the box with double walls 11 (Figs. 2 and 3) for the purpose of improving the heat insulation of the apparatus, by reason of the provision of layers of air 13. A good way of effecting in this case the enlargement of the box, is to construct the corresponding portion of the sides in the form of a single wall as shown at 17.

This arrangement affords an insulated space 12 above the upper stretch which is 110

bounded at the top by the top of the box and by the two sides of the box, and underneath by the endless band and the webs of the U bars. Another space 8 situated below the upper stretch and limited laterally by the side walls of the box and underneath by a flooring 6 provided for this purpose, communicates with the space 12 at the sides of the endless band at the end of the box at 10 7 and 7'.

The space 12 communicates with the cold air supply through a hopper 5 which distributes the air over the entire width of the endless band. This hopper 5 is situated 15 above the inlet of the endless band into the box. The space 8 is connected to the air exit trunk 9 situated on a level with the air inlet. The upper stretch of the endless band carrying the material to be cooled enters the box through a horizontal aperture 3' of small height and passes out of the box at 3 through a similar aperture. The lower stretch enters the box in like manner through an aperture indicated at 15 and 20 leaves through a similar aperture 15' (Figs. 1 and 4).

The material to be cooled is placed upon the endless band at 3'. Where such material is inclosed in molds which is the case with 30 chocolate, such molds are placed upon the endless band.

The air entering through the hopper 5 passes over the upper part of the layer of chocolate in traveling through the space 12 35 in the direction of the arrows *a*. The current of air then passes through the apertures 7 and 7' in the direction of the arrows *b* into the space 8, and travels through this space in the direction of the arrows *c* to pass 40 out through the trunk 9. During its journey the upper surface of the chocolate is cooled by the current of cold air in 12, and its surface adjacent to the endless band is cooled by the current of cold air in 8.

45 When it is desired to cool chocolate or other material contained in molds, it is an advantage to construct the endless band of members or sections separated from one another in the direction of the travel by narrow gaps. The cold air then passes partly 50 through a gap and can thus flow likewise over the sides of the molds.

It is to be noted that the U bars 14 that serve to effect the separation of the two 55 spaces 8 and 12, also serve to support and guide the upper stretch in the direction of its travel by preventing it from "whipping." It is an advantage also to provide U bars

16 for supporting the said stretch in the middle.

The apparatus illustrated in Figs. 5 and 6 comprises a box 4 for the cooler-conveyer above which there is arranged near its front end a refrigerator 18 that communicates through the hopper 5 with the box 4. The 65 air is taken from the exit trunk 9 by a pipe that conveys it to an air-drying device 19 whose exit orifice is connected to the inlet of a fan 20. The latter delivers the air through a pipe 21 into the refrigerator 18. 70 The refrigerator 18 and the air-drying device 19 have the usual construction of those kinds of devices employed in industry.

Having now particularly described and ascertained the nature of my said invention 75 and in what manner the same is to be performed, I declare that what I claim is:

1. A cooling apparatus, comprising a box; a conveyer composed of an endless band for carrying the material to be cooled through 80 said box; means for separating the spaces situated, respectively, above and beneath the upper stretch of the endless band; and means for causing a current of cold air to pass in one direction above the upper stretch of said 85 band and then beneath it in the opposite direction.

2. A cooling apparatus, comprising a box; a conveyer composed of an endless band for carrying the material to be cooled through 90 said box; horizontal supporting means carried by the side walls of the box and on which the edges of the upper stretch of the endless band are adapted to rest; and means for causing a current of cold air to pass in one direction above the upper stretch of said 95 band and beneath it in the opposite direction.

3. A cooling apparatus, comprising a box; a conveyer composed of an endless band for carrying the material to be cooled through 100 said box; and horizontal supporting means carried by the side walls of the box and on which the edges of the upper stretch of the endless band are adapted to rest; said box having an aperture disposed in its upper 105 portion adjacent one end thereof for admitting air into the space above the said upper stretch of the band, and having air passages adjacent its other end to enable the air to pass from said space below the upper stretch. 110

In testimony whereof I affix my signature in presence of two witnesses.

MAURICE MATHY.
